(57) **CLAIM**

The ornamental design for a goal having a chain curtain, as shown and described.

DESCRIPTION

FIG. 1 is a perspective view of a goal having a chain curtain; FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged detail perspective view illustrating 8-8 of FIG. 1;

FIG. 9 is an enlarged detail front elevation view illustrating 9-9 of FIG. 2;

FIG. 10 is an enlarged detail rear elevation view illustrating 10-10 of FIG. 3;

FIG. 11 is an enlarged detail left side elevation view illustrating 11-11 of FIG. 4;

FIG. 12 is an enlarged detail top plan view illustrating 12-12 of FIG. 6; and,

FIG. 13 is an enlarged detail bottom plan view illustrating 13-13 of FIG. 7.

The even-length broken lines depict portions of the goal having a chain curtain that form no part of the claimed design. The long-short broken lines, in FIGS. 8-13, illustrate bounds of the magnified portions and form no part of the claim.

1 Claim, 12 Drawing Sheets
